UNITED STATES PATENT OFFICE.

HUBERT O. LE BLANC, OF SPRINGFIELD, MISSOURI.

DESIGN FOR A COAT AND PANTS HANGER.

SPECIFICATION forming part of Design No. 33,266, dated September 25, 1900.

Application filed August 10, 1900. Serial No. 26,536. Term of patent 14 years.

To all whom it may concern:

Be it known that I, HUBERT O. LE BLANC, a citizen of the United States, residing at Springfield, in the county of Greene and State of Missouri, have invented and produced a new and original Design for a Coat and Pants Hanger, of which the following is a specification.

The invention relates to a new and original design for a coat and pants hanger; and it has for its object to provide a design of this character which will be both useful and attractive.

The leading feature of the design consists in the design forming the subject-matter of the accompanying illustration.

In the drawings, Figure 1 is a perspective view of a coat and pants hanger, showing my new and original design. Fig. 2 is a longitudinal sectional view. Fig. 3 is a transverse sectional view.

Referring to the drawings, 1 designates a hollow shell approximately triangular in side elevation and having a rounded or dome-shaped top 2 and surmounted by a hook 3. The ends 4 are slightly curved and they have

curved upper boundaries and their lower edges are straight and arranged approximately in the same plane as the lower edges 5 of the sides 6 and 7. The lower edges of the sides are straight when viewed in side elevation. The side 7, which is located at the back of the device, is curved from the top of the same to its lowest edge and is bowed longitudinally, and the front side 6, which is bowed outward in excess of the rear side, inclines downward from the top of the shell to its lower edge. The sides are provided with approximately-circular openings 8, having depending extensions 9, forming contracted continuations of the said openings 8.

What I claim is—

The design for a coat and pants hanger, substantially as shown.

In testimony that I claim the foregoing as my own I have hereto affixed my signature in the presence of two witnesses.

HUBERT O. LE BLANC.
